FOOTBALL BLOCKING SLED FOR FOREARM TESTING

Jerry L. O'Donnell, 3906 Onawa Drive,
Waterloo, Iowa 50701

Filed June 18, 1973, Ser. No. 371,261

Term of patent 14 years

Int. Cl. D10—05
U.S. Cl. D10—83

FIG. 1 is a left front perspective view of a football blocking sled for forearm testing showing my new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a rear elevational view thereof.

I claim:

The ornamental design of a football blocking sled for forearm testing, substantially as shown.
